UNITED STATES PATENT OFFICE.

WILLIAM SICKLES, OF GILMAN, ILLINOIS, ASSIGNOR OF ONE-HALF TO WILLIAM W. McDONALD, OF GILMAN, ILLINOIS.

SELF-ELEVATING HANGER OR SUPPORT.

Application filed June 17, 1922. Serial No. 569,169.

To all whom it may concern:

Be it known that I, WILLIAM SICKLES, a citizen of the United States, residing at Gilman, in the county of Iroquois and State 5 of Illinois, have invented certain new and useful Improvements in Self-Elevating Hangers or Supports; and I do hereby declare the following to be a full, clear, and exact description of the invention, such as 10 will enable others skilled in the art to which it appertains to make and use the same.

This invention relates to a supporting device or hanger.

It is aimed to provide a construction 15 whereby a hook, hooks or equivalent supporting elements are urged to their uppermost position but capable of being lowered to facilitate attachment of the articles to be supported and for instance, animal harness.

20 A second object is to provide a novel construction including a movable supporting means urged to an uppermost position in combination with novel latch means to act counter to the urgency of the supporting 25 means in order to maintain the supporting means in a lowered position facilitating attachment of the article or articles thereto.

Another object is to provide a supporting 30 means consisting of a plate to contain the supporting element or elements, mounted on rollers and adapted to travel on a wall or panel of a casing provided with a strap through which the elements project for utility.

35 Additional objects and advantages will become apparent from a consideration of the description following taken in connection with accompanying drawings illustrating one practical embodiment.

40 In said drawings:—

Figure 1 is a front elevation of the improved device;

Figure 2 is a side elevation;

45 Figure 3 is a side elevation with one of the sides removed to disclose interior details;

Figure 4 is a cross sectional view on the line 4—4 of Figure 2, looking towards the front;

50 Figure 5 is a detail perspective view of the latch means adapted to engage the weight;

Figure 6 is a detail perspective view of the sliding supporting means.

Like reference characters designate like or 55 similar parts in the different views.

In reducing the invention to practice, a suitable housing or casing is employed as at 10 which may be made of wood or other suitable material, preferably square or rectangular in cross section having a front 60 wall at 11 provided with an elongated central longitudinal slot therethrough at 12. The ends of the casing or housing are open and hoods or caps 13 may be detachably secured thereto. As one form of means which 65 may be employed to secure the caps in place, lugs 14 may be provided on the caps and on the side walls of the casing 10 and have a bolt 15 removably passed therethrough and adapted to receive winged nuts 16 thereon. 70

Within the casing 10 a support generally designated 16' is provided which is adapted to slide on the inner surface of the wall 11 and to this end employing a base or plate as at 17 having axles 18 secured thereto 75 mounting rollers 19 which travel on tracks 20 provided on said wall 11. Extending outwardly from the plate 17 and through the slot 12 are one or more supporting elements which may be hooks 21 provided with 80 suitable braces 22 extending from their free ends and inwardly and downwardly to the base 17. As shown, two hooks are utilized, the lower one preferably being smaller than the upper one. 85

Said plate 17 may be carried by an endless chain or belt 23 of any suitable construction and which is trained over rollers or wheels as at 24 and 25. Said chain 23 is preferably a sprocket chain as shown and the 90 wheels 24 and 25 sprocket wheels. Said sprocket wheels 24 and 25 are journaled on pins or shafts 26 carried by bearings 27, secured by suitable bolts 28 to the casing. In order that the chain 23 may be suitably tensioned, the opening through which bolts 28 of one set of bearings 27 passes, are enlarged or elongated as at 29. 95

A suitable means is employed whereby the support 16' will normally be maintained at 100 its highest position and urged to that position after downward movement thereof. Such means may constitute a weight 30 and the opposite ends of chain 23 are adapted to be fastened thereto in any suitable manner. Weight 30 is relatively heavy so as not only to urge the support to an elevated position but to overcome the weight of harness or other articles which may be placed on the hook 21. 105

110

A suitable means is provided whereby the support may be maintained in its lowermost position against the urgency of the weight 30 so as to facilitate the application of harness or other articles to the hooks 21. To this end, the weight 30 may have a keeper opening as at 31 into which a lug 32 is adapted to enter. The lug 32 extends through an opening 33 in the adjacent side 10 wall of the casing and is part of a latch bar 33' pivotally mounted in a bracket 34 suitably screwed as at 35 to the casing. Said latch 33' is normally urged inwardly at the lug end 32 and said lug is so shaped that as 15 the weight 30 passes the same it will automatically clip into the slot 31. The latch 33' is adapted to be operated from a point adjacent the lower end of casing 10 and in view of this fact, a draw chain or cord 20 36 may be fastened thereto at 37 and have a gripping ring 38 at its free end.

In use, the support 16' is normally elevated through the urgency of the weight 30. When harness or other articles are to be 25 placed on the hooks 21, the same are grasped and moved to a lowered position which causes the chain 23 to travel about the rollers 24 and 25 elevating the weight 30 so that its slot 31 will move opposite the lug 32 and the latter will clip into said slot and thus 30 maintain the chain 23 locked against movement and the hooks 21 in lowermost position. The harness or other articles may then be placed on the hooks 21 after which 35 element 36 is drawn downwardly which retracts the latch 33', disengaging lug 32 from the slot 31 so that the weight 30 will be released and by gravity will fall to its lower-

most position, thus elevating the support 40 and article or articles thereon.

The downward movement of the weight 30 and upward movement of the support are limited through the engagement of the plate 45 17 or uppermost hook 21 with the lower edge of the upper cap 13, since the latter 45 bridges the slot 12 and closes the same at the upper end.

As merely one practical embodiment has been illustrated and described, it is to be understood that changes in the details may 50 be resorted to provided they fall within the spirit and scope of the invention.

I claim as my invention:

A support including a casing, said casing having a wall provided with an elongated 55 slot therethrough, a support consisting of a plate within said casing, supporting means extending from the plate through said slot, an endless element carrying said plate, guide means for said element within the casing, a weight carried by said endless element provided with a slot, a latch exteriorly of and on the casing, said casing having a slot, said latch having a lug extending through said slot of the casing to engage said slot of the 60 weight, and a spring associated with the latch to urge movement thereof to cooperate with the weight in order to maintain the support in a lowered position.

In testimony whereof I affix my signature 65 in presence of two witnesses.

WILLIAM SICKLES.
